UNITED STATES PATENT OFFICE.

JOHN S. WALKER AND SYLVESTER N. WILCOX, OF PITTSBURGH, PENNSYLVANIA.

GAS-HEATER.

1,244,564.

Specification of Letters Patent. Patented Oct. 30, 1917.

Application filed January 19, 1916. Serial No. 72,880.

To all whom it may concern:

Be it known that we, JOHN S. WALKER and SYLVESTER N. WILCOX, citizens of the United States, residing at Pittsburgh, in the 5 county of Allegheny and State of Pennsylvania, have invented certain new and useful Improvements in Gas-Heaters, of which the following is a specification.

This invention relates to gas heaters and 10 has for its object to provide a heater of such class, in a manner as hereinafter set forth, which is simple in its construction and arrangement, inexpensive to manufacture, and has a combined heat retarding and retaining 15 element to facilitate the heating of cold air as the latter flows through the heater, including means to prevent escape of fumes or vapors into the atmosphere under such conditions reducing explosions to a minimum 20 when the heater is used in a garage or in proximity to explosive materials, and has an inclosed burner to overcome accidental burning of the person or ignition of materials near the heater, and is durable, strong, 25 efficient, convenient in its use, and including means to provide a heat radiating member associated with the heat retarding and retaining element.

With the foregoing and other objects in 30 view the invention consists of the novel construction, combination and arrangement of parts as hereinafter more specifically described and illustrated in the accompanying drawing, wherein is shown an embodiment 35 of the invention, but it is to be understood that changes, variations and modifications can be resorted to which come within the scope of the claims hereunto appended.

In the drawings wherein like reference 40 characters denote corresponding parts throughout the several views:

Figure 1 is a sectional elevation, partly broken away, of a gas heater in accordance with this invention.

Fig. 2 is a sectional detail of the door of 45 the heater.

Fig. 3 is a detail in front elevation illustrating the door opening, and Fig. 4 is a vertical longitudinal sectional view through the 50 device with the construction shown in perspective and taken upon a plane through the flues and door casing.

Fig. 5 is a fragmental sectional view showing more fully the air-passage or space be- 55 tween the burner and the outer wall of

chamber 6 for the upward passage of the air entering through the inlet-pipe 12.

Referring to the drawings in detail 1 denotes a cylindrical shell, having a foraminous cap 2 at the top and supporting legs 3 60 at the bottom. The legs 3 provide for the lower end of shell 1 to be maintained spaced above the support upon which said legs 3 are mounted.

Inclosed by the shell 1 is a casing constructed of outer and inner cylindrical members and which are designated respectively 4, 5. The member 5 is spaced from the member 4 forming thereby an annular heating chamber 6, in which is arranged a stationary 70 combined heat retarding and retaining element 7 of spiral form which is perforated throughout as at 8. The element 7 may be constructed of any suitable material, preferably metal and extends from near the top 75 to near the bottom of the said chamber 6.

Arranged within the chamber 6, below the lower end of the element 7, is an annular perforated metallic plate 9, which provides a heat retarding member and is positioned 80 above a gas burner 10 arranged within the chamber 6 above the bottom thereof.

The chamber 6 is closed at its top and at its bottom, and communicating with the top of said chamber 6 is an outlet pipe 11, the latter extending through the shell 1 and cylindrical member 4 and communicates with the chamber 6, and is employed for the discharge of vapors and fumes from the latter. Communicating with the chamber 6, below the gas burner 10, is an air intake pipe 12, the latter extending through the shell 1 and cylindrical member 4 and opening into said chamber 6 and is employed for supplying cold air thereto for a purpose hereinafter described.

Supported by the shell 1, near the lower end thereof and extending into the chamber 6, as well as opening into the burner 10, is a gas supply pipe 13, having a mixing element 14 and further provided with an inlet pipe 15.

The shell 1, near its lower end and above the burner 10 is formed with an opening receiving a door casing 17, the latter opening 105 into the chamber 6 and by such an arrangement access can be had for any desired purpose to said chamber 6.

Connected against the periphery of the wall 1, in any suitable manner, and sur-

rounding the door casing 17, is positioned a door frame 19 secured to the shell 1. The outer face of the door frame 19 has secured thereto and entirely around the same, a 5 length of asbestos cord 20, which is utilized to set up a seal when the door 21 is employed to close the outer end of the door casing 17. The door 21 is hinged in any suitable manner to the casing 19, and has its 10 inner face provided with a groove 22 to receive the cord 20 when the door is closed. Any desirable catch for maintaining the door closed can be employed.

The shell 1 is spaced from the member 4 15 to form an air chamber 23 open at its bottom, and with its upper end opening into the chamber whose upper wall is formed by the foraminous cap 2, before described. The member 5 provides an air conduit 28^a for the 20 passage of air and said conduit is open at its top and bottom.

The door casing 17 and the pipes 11 and 12 are utilized to support the members 4, 5, within the shell 1. As the element 7 is connected not only to the member 4, but also to the member 5, it maintains said members in spaced relation. If desired an additional means can be employed for supporting the members 4, 5, within the shell.

30 The top and bottom of the chamber 6 is closed by annular plates, 24, 25 respectively, and the upper and lower joints between the plates and the cylindrical members 4, 5, are sealed by inclined metallic strips 26 and asbestos strips 27, these latter being interposed between the strips 26 and members 4, 5. The strips 26 and plates 24, 25, are welded or otherwise secured to the members 4, 5.

40 It will be understood that the flues 11 and 12 are arranged upon the side of the shell 1 substantially opposite the door-casing 17 and may be positioned in the directly opposite side thereof as seen in Fig. 4. With the 45 use of the perforated spiral member or baffle-plate 9, the ascending combustion-products and air are divided up into streams, portions thereof passing through the perforations in said baffle plate and other portions being caused to travel helically upwardly along the latter until exhausted through the outlet flue 11, the air admitted into the chamber 6, and passing upwardly around the burner, providing for the effective 50 combustion of the gaseous products arising from the burner, and passing cir-

cuitously upwardly along the spiral baffle-member.

What we claim is:—

1. A heater comprising an upright open- 60 ended shell, a rectangular door casing and cylindrical inlet and outlet flues secured through said shell upon different horizontal planes projecting inwardly of the shell, the said casing being upon substantially the 65 opposite side of the shell from said flues, a hot-air drum axially positioned within said shell and solely supported by the inner terminal ends of said casing and flues, the said drum having a tubular inner wall forming 70 an open longitudinal hot-air passage centrally through the shell, and a heating burner within the drum above said inlet flue and below the level of said door casing and accessible through the latter. 75

2. A heater comprising an open-ended outer shell, a perforated hot-air outlet member for the upper end of the shell, a lower inlet and an upper outlet flue, a door casing arranged in an intermediate plane with respect to said flues, said casing and flues being secured through said shell and projecting inwardly thereof, a cylindrical hot-air member axially supported within said shell and fixed upon the inner ends of said casing and flues through which cylindrical member the same extend communicating with the interior thereof, a tubular member axially arranged within said cylindrical member and connected therewith at the top and bottom thereof, forming an annular heating chamber, an annular burner within said heating chamber below the level of said casing, an annular perforated radiating plate above said burner in parallelism therewith 90 lying substantially in the same horizontal plane as the said casing adapted for separating the ascending gases, and a perforated heat retarding and retaining member spirally positioned within said casing intermediate said plate and outlet flue whereby a portion of the ascending gases pass vertically therethrough and a portion thereof pass helically toward the said outlet flue. 95

In testimony whereof we affix our signatures in the presence of two witnesses.

JOHN S. WALKER.
SYLVESTER N. WILCOX.
